UNITED STATES PATENT OFFICE.

JOHN ALGOTS, OF CHICAGO, ILLINOIS.

DESIGN FOR A BICYCLE LUNCH-BOX.

SPECIFICATION forming part of Design No. 31,403, dated August 15, 1899.

Application filed July 10, 1899. Serial No. 723,425. Term of patent 3½ years.

To all whom it may concern:

Be it known that I, JOHN ALGOTS, a citizen of the United States of America, and a resident of Chicago, in the county of Cook and State of Illinois, have invented a new and original Design for Bicycle Lunch-Boxes, of which the following is a specification, reference being had to the accompanying drawings, forming a part thereof.

10 Figure 1 is a perspective view of a lunch-box made according to my new design. Fig. 2 is a side elevation of same. Fig. 3 is a vertical section on the line $x x$ of Fig. 2.

The leading or material feature of my design consists in the general contour of the box, the same being oblong in outline and of less thickness than its height or length, being of substantially the same appearance on each side, rounded at the corners, having the 15 raised panel on each side and the ridge or rib surrounding the box where the sides meet.

The box is formed of two concavo-convex sheet-metal members 1 and 2 of substantially

the same form and size, except that the member 1 has its flange 3 spun inwardly slightly, 25 so as to fit within the flange 4 of the member 2. The body of each of the members 1 and 2 has its four corners 5 rounded, as shown, and the panels 6 pressed outwardly. The rims 7 and flanges 3 and 4 together form the 30 ridge surrounding the box. The members 1 and 2 are connected by hinges 8 and each carry the strap-loops 9 at their upper corners and the similar loops 10 at one of the lower corners.

What I claim as new, and desire to secure by Letters Patent, is—

The design for a bicycle lunch-box, substantially as herein shown and described.

Signed by me, at Chicago, Illinois, this 8th 40 day of July, 1899.

JOHN ALGOTS.
